United States Patent Office.

HENRY McGANN, OF CLEVELAND, OHIO.

Letters Patent No. 78,224, dated May 26, 1868.

IMPROVEMENT IN DEVICE FOR FEEDING BOILERS.

The Schedule referred to in these Letters Patent and making part of the same.

TO ALL WHOM IT MAY CONCERN:

Be it known that I, HENRY McGANN, of Cleveland, in the county of Cuyahoga, and State of Ohio, have invented certain new and useful Improvements in Water-Regulator for Steam-Boilers; and I do hereby declare that the following is a full and complete description of the same, reference being had to the accompanying drawings, making a part of this specification, in which—

Figure 1 is a front view of the apparatus,

Figure 2 a side view,

Figure 3 a vertical section,

Figure 4 detached sections.

Like letters of reference refer to like parts in the several views.

In fig. 1, A represents the case or shell in which the pendulum B swings from the shaft C, fig. 4, said shaft being projected through the side of the case, and in which it has its bearings.

To the lower end of the pendulum is attached a float, D, the purpose of which will hereinafter be shown.

To the outer end of the shaft C is keyed an arm, E, the lower end of which forms the segment of a circle, from which proceed cogs, which are made to engage in the cog-wheel F. Said wheel is keyed to the plug G, fig. 4, of the water-cock H, fig. 2, and by which it is turned, as follows:

The apparatus is fixed to the head of the boiler, or at any other appropriate place, and at such a point in relation to the water, that the pendulum will hang vertically, as shown in fig. 3, when the water is at the lowest point of safety.

The shell or case is put in communication with the boiler by pipes leading from the same, and connected to the case at the ends H', into which they are screwed.

By this it will be obvious that the water will flow from the boiler into the shell, and that it will always be at the same height in the case as it is in the boiler, as a direct and free communication is established between them.

As the water is raised in the boiler to the highest water-line, so also will the water in the case be raised to the same point, the result of which will be to carry or float upward the ball D, but which, in consequence of being attached to a straight, rigid pendulum, will, as it floats upward, carry the pendulum to one side, as indicated by the dotted lines a.

The pendulum, as above said, being connected to the shaft C, will cause the stem or plug of the cock to turn, which will give to the segmental arm E a vibratory movement, which, actuating the wheel F, will cause it to turn, and with it the plug of the cock, thereby stopping it, shutting off the inflowing water from the boiler at the highest water-line. Now, as the water may descend in the boiler, so also will it descend in the shell, and as it recedes from the highest water-line toward the lowest, the float will fall, and thereby open the cock and allow the water before stopped out to flow into the boiler, and thus prevent its descent below the line of safety.

As the boiler begins again to fill by the inflowing of the water, the float will also rise, operating the cock, and entirely shutting the same when the water rises to the highest water-line.

By this self-acting regulator the water in the boiler can never fall below the lowest water-line; hence all danger of a collapse and explosion arising from a deficiency of water can never take place, as the boiler is constantly kept supplied to its required height.

What I claim as my improvement, and desire to secure by Letters Patent, is—

The arrangement of the pendulum B, shaft C, case A, segmental arm E, wheel F, and cock H, substantially as herein specified.

HENRY McGANN.
